UNITED STATES PATENT OFFICE.

ARCHIBALD JACKSON STRANE, OF TAMAQUA, PENNSYLVANIA, ASSIGNOR TO ATLAS POWDER COMPANY, OF WILMINGTON, DELAWARE, A CORPORATION OF DELAWARE.

MACHINE FOR ASSEMBLING SHELLS.

1,334,326.

Specification of Letters Patent. Patented Mar. 23, 1920.

Application filed June 13, 1919. Serial No. 304,012.

To all whom it may concern:

Be it known that I, ARCHIBALD JACKSON STRANE, a citizen of the United States of America, residing at Tamaqua, in the county 5 of Schuylkill and State of Pennsylvania, have invented certain new and useful Improvements in Machines for Assembling Shells, of which the following is a specification.

10 This invention relates to a machine for assembling shells in shellholders and the object of the invention is to provide an improved device of this character by means of which empty shells of various kinds may 15 be automatically and rapidly fed to and placed in position, open end up, in shellholders, preparatory to loading said shells or, in the case of shells that have been loaded, assembling said shells in proper position in final containers.

Further objects and advantages of the invention will be set forth in the detailed description which now follows.

In the accompanying drawings Figure 1 25 is a vertical sectional view of a machine constructed in accordance with the invention with the mechanisms of the several parts diagrammatically illustrated; Fig. 2 is a transverse vertical section through a 30 part of the bottom of a hopper hereinafter described, and Fig. 3 is a plan view of the machine. Like numerals designate corresponding parts in all of the figures of the drawing.

35 While I have, for the purpose of illustration, shown the machine in relation to its use for assembling ordinary paper shells having metallic ends it will be understood that the machine is designed to assemble any character of shell having one of its ends closed or, in other words, so constructed that one of the ends is heavier than the other when the shell is poised substantially midway of its length.

45 The machine comprises a hopper 5 having an inclined bottom 6. This bottom is grooved at 7 to form a plurality of guideways down which the shells slide by gravity into and through tubes or channels 8, alined 50 with the grooves 7. The bottom of the hopper is slotted as indicated at 9 between each of the grooves 7 and the teeth 10 of a comb operate through these slots as hereinafter set forth and exert a raking upon

shells deposited in the hopper 5 to cause 55 said shells to be deposited lengthwise in the grooves. It is apparent that this raking action can do no more than cause the shells to lie longitudinally in the grooves, it cannot determine which end will be disposed downwardly and the result is that the closed ends of some of the shells will be disposed downwardly and the open ends of other of the shells will be disposed downwardly and in this position the shells will 60 pass through the channels 8. To provide an escapement mechanism by which the shells may be fed one by one through the several tubes 8 a rock shaft 12 is disposed across the entire battery of tubes, said shaft 65 carrying a plurality of fingers 13 that are fixed to said shaft and a plurality of fingers 14 that are yieldably connected to said shaft by springs 15. Any suitable means may be employed for imparting oscillatory movement to shaft 12, such for example, as an arm 16 upon the said shaft which depends into the path of movement of an actuating member hereinafter described.

The shells which pass downwardly through 80 the tubes or channels 8 are received in arcuate grooves 17 formed in a tipple plate 18. This plate is pivoted to swing about an axis indicated at 19, and a spring 20 functions to move said plate upwardly against a fixed 85 stop 21. When at its upper limit of movement the tipple plate aligns with the tubes 8. A fixed stop bar 22 carries goose necks 23 which constitute abutments against which the lower ends of the shells come to rest 90 and these goose necks are provided with threaded stems 24 that may be adjusted through the bar 22 by means of nuts 25. It will be apparent that this constitutes an adjustment by which it may be determined how 95 far the shells will be permitted to pass into the pockets 17. This renders it possible to take care of shells of varying lengths in the same machine. The tipple plate is provided with a longitudinally extending groove 26 100 which traverses all of the pockets 17 and lies substantially midway of the length of the shells when said shells are in a position of rest in said pockets. A knife edge is disposed below and in alignment with the 105 groove 26 and is adapted to enter said groove when the tipple plate is lowered to the dotted line position illustrated in Fig. 1. This

knife edge is disposed between the open ends of a plurality of pairs of conducting tubes 28, 28^a, it being understood that there is a pair of these tubes related to each of the 5 pockets 17 and it will be observed that these tubes 28, 28^a, merge into common conducting tubes 29 and the function of the machine is to deliver the shells open end up into the several tubes by which they are conducted 10 to the shellholders, not shown.

The parts so far described constitute the essential elements of the machine. It is clear that various ways of actuating these several movable parts may be resorted to 15 within the range of mechanical skill. It is therefore to be understood that the connections described for imparting movement to the several parts are diagrammatic only and have been illustrated merely for the purpose 20 of outlining an operative structure. To this end I have indicated a driven shaft 30 actuated by a pulley 31 and driven by a belt 32. A belt 33 drives a shaft 34 which carries a plurality of sprockets 35 over which chains 36 pass, and it is these chains that carry the teeth 10 of the comb. It will readily be seen 25 that these teeth pass upwardly through the lower portions of the slots 9 and travel rearwardly in elevated positions and then descend and pass forwardly while out of engagement with the shells. A belt 37, by means of a pulley 38, drives a disk 39 that carries a pin 40. This pin operates in a slot 41 of a link 42 that is connected to one arm 30 of a bell crank lever 43. The other arm of this bell crank lever is connected by a link 44 with the tipple plate 18. During the rotation of the disk 39 the pin 40 engages the left hand end of the slot 41 and a pull is 35 imparted to the link 42 which results in pulling the tipple plate down to the dotted line position illustrated in Fig. 1, and against the tension of the spring 20. Thereupon the knife edge 27 enters the groove 26 and engages all of the shells in the battery of pockets 17 substantially midway of their lengths and tends to lift them. The shells will thereupon tip in one direction or the other according to the way their heavy 40 ends are disposed. If the heavy end of a shell is disposed downwardly the shell will tip to the right in Fig. 1 while if the heavy end of a shell is disposed upwardly said shell will tip toward the left in that figure. Since 45 it is the heavy end of the shell that tips downwardly in each instance, it follows that the lower ends of the shells will first enter the tubes 28, 28^a and consequently all of the shells will pass from the tube 29 with their 50 closed ends downward. By providing the goose necks 23 and arranging these goose necks as shown these parts act as stops for the shells and continue to exercise their function of preventing further downward movement of the shells under the influence of 55

gravity until after the tipple plate 18 has moved toward the dotted line position illustrated in Fig. 1, to and beyond the angle of repose of the shell. In other words by the time the shells move downwardly until 70 they are free of the goose necks 23 they have moved to such a position that they no longer tend to move endwise under the influence of gravity and they will remain in the position to which they have been adjusted by the 75 goose necks until they are engaged by the knife edge 27 and will tip in one direction or the other. A belt 45, a pulley 46, a shaft 47, and fingers 48 on said shaft constitute conventional means for imparting movement 80 to the arm 16 against the tension of a spring 16^a whereby oscillatory movement is imparted to the rock shaft 12. When one of the fingers 48 contacts with the arm 16 initial movement of the rock shaft causes the 85 finger 14 to engage the shell *a* and to hold the line of shells from further downward movement. The yielding mounting of the finger 14 with respect to the rock shaft permits continued movement of the arm 16 90 enough to raise the arm 13 out of blocking position with respect to the shell *b*, whereupon said shell is permitted to slide down into the corresponding pocket of the tipple plate. The yielding mounting of the finger 95 14 with respect to the shaft 12 causes this finger to continue to exercise its holding function after the arm 16 starts to return to the full line position illustrated in Fig. 1 and to bring the finger 13 into blocking position and this holding action of the finger 14 continues until the finger 13 has actually 100 reached blocking position after which the continued improvement of the arm 16 lifts the spring finger slightly out of contact with the shell *a* and permits the shell to slide down into contact with the finger 13.

It is to be understood that the invention is not limited to the arrangement and construction set forth but that it includes within its purview whatever changes fairly come within either the terms or the spirit of the appended claims.

Having described my invention what I claim is—

1. In a machine of the character described the combination with a shell receiving element of a shell engaging element adapted to engage the sides of the shells, means for moving one of said elements with relation to the other to bring the shell engaging element into contact with said shells to tend to poise them thereon and members for receiving said shells as they tip in one direction or the other from the shell engaging element.

2. In a machine of the character described the combination with a shell receiving element of a shell engaging element adapted to engage the sides of the shells, means for moving one of said elements with relation

to the other to bring the shell engaging element into contact with said shells to tend to poise them thereon, conducting members for receiving said shells as they tip in one direction or the other from the shell engaging element and common conducting members to which the first named conducting members lead.

3. In a machine of the character described 10 the combination with a tiltable plate having a shell receiving pocket formed therein of means for feeding shells endwise into said pocket and a shell engaging element traversing said pocket and adapted to engage 15 the side of the shell and means for imparting movement to said tiltable plate to bring the shell into engagement with the shell engaging element to cause said shell to tip in one direction or the other according to the 20 direction in which its heavy end is disposed.

4. A structure as recited in claim 3 in combination with a stop for limiting the movement of the shell into said pocket and means for adjusting said stop.

25 5. In a machine of the character described the combination with an element having pockets and tiltable from an inclined to a substantially horizontal position, means for feeding shells gravitally thereinto and a 30 member adapted to engage the shells at their sides and intermediate of their ends upon

the movement of the said element toward a horizontal position.

6. A structure as recited in claim 5 in combination with a stop adapted to limit 35 the movement of the shells into said pockets said shells moving out of engagement with said stop upon movement of the said element toward horizontal position.

7. A hopper having a plurality of longitudinal grooves in its bottom, slots formed in the bottom between said grooves and a rake or comb the teeth of which are operable in said slots to longitudinally aline shells in 45 said grooves.

8. In a device of the character described the combination with a tiltable element having a plurality of pockets formed therein, into which the shells are delivered gravitally from said conduits, said tiltable element 50 having a groove formed therein traversing all of said pockets and an edged element disposed below the tiltable element adapted to enter said groove and engage the sides of the shells and means for moving the tiltable element toward said edged element. 55

In testimony whereof I affix my signature in the presence of two witnesses.

ARCHIBALD JACKSON STRANE.
